COMBINATION PADLOCK

Francisco Toscano, Los Banos, Calif.

Application November 1, 1932. Serial No. 640,605

3 Claims. (Cl. 70—113)

This invention relates to padlocks having a combination locking device for holding the shackle against opening movement and in which the setting of the proper combination releases the shackle without the use of a key.

The principal object of my invention is to provide a lock of this general character so constructed that the combination can be set and of course broken in the dark, and one in which the combination may be easily changed at the option of the owner with very little trouble. The lock is also very silent in operation so that it would be hard for an unauthorized person to tell whether he was attaining the desired end or not by sound.

15 A further object is to arrange the parts of the lock so that there is no danger of any detrimental strain being placed on the combination discs or tumblers with any attempt to pry the shackle loose from its locked position, without necessitating making such discs very heavy, so that the lock mechanism may be kept in relatively compact and non-bulky form while still having ample strength for its purpose.

20 A further object of the invention is to produce a simple and inexpensive device and yet one which will be exceedingly effective for the purpose for which it is designed.

25 These objects I accomplish by means of such structure and relative arrangement of parts as will fully appear by a perusal of the following specification and claims.

In the drawings similar characters of reference indicate corresponding parts in the several views:

30 Figure 1 is a side elevation of the padlock with the shackle in its locked position.

35 Fig. 2 is a sectional elevation of the padlock with the shackle held locked.

Fig. 3 is a similar view showing the locking discs turned to release the shackle.

40 Fig. 4 is a perspective view of the upper cap unit and shackle detached from the body.

Fig. 5 is a sectional plan on the line 5—5 of Fig. 3.

45 Fig. 6 is a perspective view of the tumbler and dial assembly showing the combination broken.

Fig. 7 is a similar view showing the position of the discs subsequent to the initial combination setting operation.

50 Fig. 8 is a similar view showing the position of the discs subsequent to the second setting operation.

Fig. 9 is a similar view showing the combination fully set subsequent to the third setting operation.

55 Referring now more particularly to the char-

acters of reference on the drawings, the numeral 1 denotes the body of the lock—a hollow cylindrical member having top and bottom caps 2 and 3 respectively permanently secured to the body in a suitable manner. Under and spaced from the top cap is what may be termed a false cap 4. A spindle 5 is turnably mounted in and extends between the caps 4 and 3 and below the latter is provided with a removable finger knob 6.

60 Fixed on the spindle just above the bottom cap is a dial member 7 having peripheral numbers 8 thereabout one at a time of which is visible through an opening 9 in the body. The numbers are preferably of luminous paint so that they are readily visible in the dark.

65 Turnably centered on the spindle between the dial and the cap 4 are the tumbler discs 10, 11 and 12 respectively reading upwardly from the bottom and held apart by spacers on the spindle. These discs align with notches 14 cut in one leg 15 of the shackle 16 when said shackle is in its depressed position; the other leg 17 of the shackle being slidably and turnably mounted in the body beyond the periphery of the discs. The leg 15 is 70

75 slidable in a tube 18 depending from the cap 4 into the body in opposed relation to the leg 17, said tube having notches 19 aligned with the discs and into which said discs project in movable but close fitting relationship as regards their upper edges.

80 The discs also project into the shackle notches and each is provided with a peripheral notch 20 shaped to follow the contour of the shackle leg as shown in Fig. 5 so that when the discs are turned so that all the notches align with each other and with the shackle the latter can be withdrawn.

85 The manner in which the discs are turned to place the notches into or out of alignment with each other and with the shackle so as to set or break the combination is as follows.

90 Projecting upwardly from the dial 7 in offset relation to the spindle is a pin 21 adapted to project into any one of a number of holes 22 drilled through the adjacent disc 10 concentric with the spindle. The lower portion of the pin 95

is in the form of a screw 21a mounted in the dial for longitudinal movement for the purpose which will be seen later. The head of the screw when the dial is turned to certain combination setting positions, aligns with corresponding openings 23 in the bottom cap 3 of the body as shown in Fig. 2.

100 The disc 10 has a pin 24 projecting upwardly from between adjacent holes 22 and riding in a slot 25 of great arcuate length in the disc 11.

110

Similarly the disc 11 has a pin 26 projecting upwardly from between the ends of the slot 25, said pin riding in a shorter slot 27 in the disc 12.

In operation to set the combination from a broken position, as in Fig. 6 for instance, the knob is turned to the left until a certain predetermined number of the dial appears through the body opening 9. With this initial turning the disc 10 of course constantly turns therewith, the disc 11 is finally turned somewhat by the engagement of the pin 24 with one end of the slot 25, and the disc 12 is subsequently turned by the engagement of the pin 26 with one end of the slot 27, so that said disc 12 is turned to place its notch 20 in alignment with the shackle leg 15, as shown in Fig. 7.

Upon the turning the knob to the right a certain arcuate amount or so that another predetermined number on the dial appears through the opening 9, the disc 10 will again turn, finally turning the disc 11 to its set position without disturbing the disc 12, or as shown in Fig. 8. The dial is then again turned to the left to bring another dial number in exposed position in the opening 9, which turns the disc 10 to its set position without moving the dials 11 and 12 from their previously set positions or as shown in Fig. 9. The three dial notches then align with the shackle notches permitting the shackle to be drawn up from the body to a clear position.

It will be noted from Fig. 5 that the discs are always engaged in the notches 19 of the tube 18. Thus if an attempt is made to pull the locked shackle out of the body the discs will be immediately pulled against the unyielding tube 18 and held against probable bending by reason of the pulling pressure on the shackle. The discs may therefore be made relatively thin without loss of strength for their purpose.

Leaf springs 28 are mounted in the body and pressingly engage the sides of the various discs to restrain movement of the same once they have been set. If at any time it is desired to change the combination the knob 6 is removed, which more freely exposes the holes 23 in the adjacent body cap 3. The screw 21a is then turned from the opening 23 with which it is then aligned to withdraw the pin 21 from the hole 22 with which it was previously engaged, and the dial is then rotated leaving the disc stationary until the pin aligns with another hole in the disc and body cap. The pin is then re-engaged with the disc which as will be evident changes the position of the various discs and pins relative to each other and requires a different extent of rotation of the dial in one disc or the other to set the discs.

From the foregoing description it will be readily seen that I have produced such a device as

substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A padlock comprising a body, a shackle having opposite legs slideable in the body, one of said legs having notches therein, a spindle turnably mounted in the body parallel to the shackle legs, a plurality of tumbler discs separately turnable on the spindle and aligned with the leg notches to cooperate therewith, cooperating means to cause said discs to be rotated in predetermined order by the rotation of the lower disc, said discs also having notches to align with the leg notches for releasing the shackle, the lowermost disc having a series of holes concentric with its axis, a graduated dial fixed on the spindle in the body below said disc, a screw pin mounted in the dial parallel to the spindle and adjustable axially for engagement and disengagement with any disc hole selectively, the adjacent end of the body having holes spaced the same as the disc holes to expose the adjacent end of the pin to the outside of the body to permit of the adjustment of the same.

2. A padlock comprising a body, a shackle having opposite legs slideable in the body, one of said legs having a notch therein, a spindle turnably mounted in the body parallel to the shackle legs, locking means for the shackle including a tumbler disc to engage with the leg notch and having also a notch to align with the leg notch for releasing the shackle, said disc having a series of holes concentric with its axis, a graduated dial fixed on the spindle within the body, the latter having an opening through which the dial graduations are visible, a hand knob on the outer end of the spindle for turning the same, and selectively adjustable means operable without disturbing the shackle from any position for connecting said disc and dial in different positions relative to each other.

3. A padlock comprising a body, a shackle having opposite legs slideable in the body, a spindle turnable in the body and operable from exteriorly of the same, means to lock the shackle against movement including a member concentric with and turnable relative to the spindle and selectively adjustable means operable without disturbing the shackle from any position for connecting the member and spindle in driving relationship in different positions relative to each other.
